(57) **CLAIM**

The ornamental design for a dental dispenser, as shown and described.

DESCRIPTION

FIG. 1 is a front view of a dental dispenser showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a reference perspective view showing state in which extrusion portions are completely protruded; and,

FIG. 9 is a reference perspective view showing state of use thereof.

The broken lines in the drawings depict environmental subject matter only and form no part of the claimed design.
